UNITED STATES PATENT OFFICE.

ARTHUR L. BREITENSTEIN, OF AKRON, OHIO, ASSIGNOR TO WORLD TIRE CORPORATION, OF CHICAGO, ILLINOIS, A CORPORATION OF NEW YORK.

DESIGN FOR A TIRE-TREAD.

55,411.

Specification for Design.

Patented June 8, 1920.

Application filed March 26, 1920. Serial No. 369,105. Term of patent 14 years.

To all whom it may concern:

Be it known that I, ARTHUR L. BREITENSTEIN, a citizen of the United States, and resident of Akron, in the county of Summit and State of Ohio, have invented a new, original, and ornamental Design for Tire-Treads, of which the following is a specification, reference being had to the accompanying drawing, forming a part thereof.

The figure is a plan view of a section of a tire tread showing my design.

I claim:

The original design for a tire tread.

ARTHUR L. BREITENSTEIN.

Witness:

F. B. CURRAN.
